UNITED STATES PATENT OFFICE.

CHRISTIAN MANN, OF WALDSHUT, GERMANY.

SPREADER FOR SILK, COTTON, RAMIE, OR THE LIKE.

SPECIFICATION forming part of Letters Patent No. 781,892, dated February 7, 1905.

Application filed August 1, 1904. Serial No. 219,151.

To all whom it may concern:

Be it known that I, CHRISTIAN MANN, a citizen of Germany, residing in Waldshut, Grand Duchy of Baden, Germany, (whose post-office address is Waldshut,) have invented certain new and useful Improvements in Spreaders for Silk, Cotton, Ramie, or the Like; and I do hereby declare the following to be a full, clear, and exact description of the invention, 10 such as will enable others skilled in the art to which it appertains to make and use the same, reference being had to the accompanying drawings, and to letters of reference marked thereon, which form a part of this specification. 15

I have applied for patent in France on February 3, 1904; in Germany on February 6, 1904; in Great-Britain on February 6, 1904; in Italy on February 8, 1904; in Switzerland 20 on February 11, 1904, and in Austria on February 17, 1904.

Spreaders at present in use, such as Harrison spreaders and intersecting spreaders, have the defect that the parts which convey the 25 fibrous material (the fallers and rollers) are very speedily worn out and that the expense of keeping the machine in order is consequently very heavy. Moreover, it often happens that the fibrous material is damaged by 30 being handled by the conveying parts or by coming in contact with lubricating-oil, which occurrences naturally diminish the value of the finished material to a considerable extent. As it has hitherto proved impossible to provide automatically-actuated cleaning devices 35 for these conveying parts, it has been necessary to clean them by hand, a circumstance which also injuriously affects the capacity of the machine. In the spreaders hereinafter 40 described with the aid of the drawings these defects are overcome by having the fibrous material conveyed from the delivery-roller to the drawing-rollers by means of endless belts arranged one above the other, the adjacent 45 sides of which belts move in the same direction and are set with teeth or pins, any impurities that may happen to adhere to the teeth or pins being removed by means of an artificially-produced current of air.

50 In the accompanying drawings Figure 1

represents a section drawn on the line A B of Fig. 2; Fig. 2, a plan, the fan assumed to be removed; and Fig. 3 represents a detail.

In the frame *b*, which is mounted on the stand *a*, the rollers *e e'* and *f f'* are mounted 55 in the bearings *d*, which can be adjusted by means of the screws *c*, the two rollers *e e'* moving in opposite directions, but with the same speed, being actuated in the usual manner. Over these pairs of rollers run endless 60 belts *g g'*—made, for instance, of leather or india rubber—which are set with pins or teeth *h*, that are bent backward in relation to the direction of movement of the fibrous material. These pins or teeth extend beyond the surface 65 of the belts to which they are attached, and their backs engage with the grooves or recesses formed between each two adjoining teeth or ribs of the rollers *e e'*, Fig. 3. As a consequence the belts are compelled to move 70 with a speed equal to the surface speed of the rollers. A rotary fan *i* is mounted above the right-hand end of the belts. The rotation of the fan produces a current of air in a direction contrary to that in which the belts 75 move, which current carries away any impurities that may happen to have been adherent to the belts. To the left of the pair of belts is situated a conveying-belt which moves around a roller *l* and the delivery-roller *m*, 80 which is placed above the roller *l*. Adjoining the right-hand end of the pair of belts are situated the drawing-rollers *n n*, which rotate with a surface speed greater than that 85 of the pair of belts.

The fibrous material is fed onto the conveying-belt *k*, which, assisted by the delivery-roller *m*, carries it between the two belts *g g'*, which convey it to the drawing-rollers *n n*. As soon as the ends of the fibers are gripped 90 by the rollers *n n* the fibers begin to move with the same speed as said rollers, with the result of extending the fibers, the other ends of which still adhere to the teeth or pins *h*. Experience has shown that it is possible to 95 drive the belts with a comparatively high speed without causing the fibers to curl and that the capacity of the machine is superior to those constructed in accordance with any of the systems hitherto in use. The pins or 100

teeth are very little damaged by use. Consequently the repairs are reduced to a minimum. As the belts do not require to be lubricated, it is practically impossible that the fibrous material should be soiled by oil. Moreover, the fibers being drawn out in a straight line are preserved as much as possible, and the drawing out of the long and short fibers is uniform.

Several pairs of belts may of course be arranged by the side of each other.

What I claim is—

1. The combination of a frame, delivery-rollers, drawing-rollers, a continuous belt arranged between said delivery and drawing rollers, means for sustaining said belt, pins or teeth carried by said belt and bent reversely to the direction in which said belt moves, and a means for delivering a blast against said pins or teeth in the direction in which they are bent, substantially as described.

2. The combination of a frame, delivery-rollers, drawing-rollers, two continuous belts arranged face to face, means for sustaining said belts and for causing them to travel in

reverse directions, pins or teeth carried by 25 said belts, those on each belt being bent in a direction reverse to that in which belt travels, and a means for delivering a blast against the pins or teeth on one belt in the direction in which said pins are bent, substantially as described.

3. In a spreader for silk, cotton, ramie and the like, the combination of a continuous belt, a means for supporting and advancing said belt comprising a roller having longitudinal 35 surface grooves, and rows of pins or teeth penetrating said belt and having their butt-ends protruding from the back surface of the belt, said rows of pins being spaced to coincide with the spacing of the grooves in said 40 roller, substantially as described.

In testimony that I claim the foregoing I have hereunto set my hand this 19th day of July, 1904.

CHRISTIAN MANN.
